UNITED STATES PATENT OFFICE

MARTEN JOHANN HUIZINGA, OF HAARLEM, NETHERLANDS

BIDDING APPARATUS

Application filed February 11, 1926, Serial No. 87,713, and in the Netherlands February 18, 1925.

This invention relates to a signalling—or indicating device so constructed that it enables any desired number of persons to give a signal, as for instance at auctions where, 5 while the auctioneer increases or reduces the prices, a purchaser will at a given moment indicate that he wishes to purchase.

Various arrangements of this kind are known, all of which are operated by means of 10 electromagnetic relays.

Notwithstanding that the said devices have already proved to constitute a considerable improvement over the manner of bidding formerly employed, so that the highest bidder 15 may be determined, with more certainty it has appeared in practice that with the said arrangements there is the disadvantage that if two or more persons give the signal simultaneously or almost simultaneously, the said 20 signal is not always transmitted in proper order or the right order can not always be traced. The possibility that when a certain amount is called two or more persons will exactly simultaneously operate the bidding 25 apparatus, to indicate their desire to purchase, may be neglected. There will almost invariably be a space of time between the moments the apparatus is operated by the relative persons, which space of time however 30 may sometimes be very small, and therefore will only manifest itself when the velocity with which the apparatus functions is not hindered by mechanical or other influences due to the construction or the arrangement 35 of the apparatus.

According to the invention the signalling apparatus in question is constructed so that when a signal is given the signal itself prevents another person from giving such signal, 40 at the same time thereby securing the desired accuracy above referred to.

According to the invention, use is made of a signalling apparatus which starts operating at a predetermined voltage but which 45 as soon as it has come into operation, automatically reduces the voltage on the other signalling apparatuses arranged parallel therewith to so low a value that they are prevented from coming into operation. To this 50 end use is made of a peculiarity of the so-

called glow discharge tubes, which are tubes filled with inert gases and which are without filament, which hitherto were often used for advertising purposes, that is as the so-called "letter lamps". It is a characteristic 55 of these kinds of lamps that they start lighting at a voltage of for instance 220 volts and continue lighting even if the voltage is decreased to e. g. 140 volts, but that they do not start lighting at such low voltage. 60

The invention will be made clear by the description of the arrangement which herebelow is described by way of example and which is illustrated by the accompanying 65 drawing.

In the said drawing, g_8 represent a plurality of glow lamp discharge tubes of the same type, connected in parallel, which each are connected in series with a push or other contact device as shown in the drawing. The tubes are arranged in parallel with an ordinary direct—or alternating current conductor of for instance 220 volts or a battery or other source of current, whilst the whole system is preceded by a common series resistance W , which may be of the order of magnitude of the internal resistance of a glowing tube. If now a circuit of one of the contact devices is closed the tube included 70 therein will be lighted by the full voltage of 220 volts, which is higher than the discharge voltage. As soon as the lamp is lighted the potential drops to a value which will be dependent in inverse ratio on the 75 value of the series resistance. For example, the series resistance is 8000 ohms and the lighted tube has a resistance of 16000 ohms then the voltage will be decreased from 220 80 volts to approximately 140 volts. This voltage is not sufficient to light the other lamps, 85 so that in this way the whole signalling device is put out of operation for the other purchasers until the first purchaser has released his contact. It is obvious that one of the greatest advantages of the invention is 90 to be seen in the fact that the discharge phenomenon in the lighted lamp gives a signal and at the same time prevents the lighting of the other lamps. 95

As stated above the device may be supplied 100

with direct current as well as with alternating current. The discharge voltage of the tubes may not vary too much, which applies also to the minimum potentials, the series resistance being designed to reduce the voltage below the discharge voltage of any of the other tubes.

Discharge voltage and minimum light voltage will depart from each other more according to the tubes being designed for starting at a higher voltage.

Sometimes it is preferable to arrange the contact devices between the tubes and the common series resistance so that they are protected at both sides by a rather high resistance.

The invention is not limited to the above mentioned application but may also be carried out in other ranges as for instance in calling devices in telephony or in signalling systems for railways. The apparatus may also be operated at voltages quite different from those mentioned by way of example, such voltage depending in large measure on the gases with which the tubes are filled and on the shape and the dimensions of the electrodes. The intensity of the light may be made higher than with ordinary glow discharge tubes.

If the signalling device described hereabove, is used with a bidding apparatus which is provided with an electric auctioneer then the circuit may be provided with a device such for instance as a relay which stops the auctioneer. The winding of said relay may have such a resistance that it may be substituted for the resistance W . Further it is possible to impress the voltage difference, which occurs at the terminals of resistance W when current is flowing through it, upon a thermionic device, whereby a current variation is caused in the plate circuit thereof, which operates the braking device of the electric auctioneer.

The drawing indicates how the potential difference which occurs between the terminals of the resistance W , when one of the contacts is closed, may be used to stop the indicator of the automatic auctioneer. To that end the said potential difference is impressed upon a thermionic amplifier of any well-known type, represented in the figure by the rectangle A . The amplified current produced in the output circuit thereof energizes the magnet M which in turn pulls the pawl P between the teeth of the pinion R associated with the indicator of the auctioneer which thereby is forced to stop.

Further it may be desirable to provide a device, which holds the contact even if the push is released, which contact may afterwards be broken by a manipulation of the auction master.

To this end a pawl and spring B may be provided which holds the contact-pin when it

is depressed, said spring being adapted to be withdrawn either by the tenant of the said apparatus or by means of an electromagnet N , the energizing circuit O, L of which is controlled by the auction master.

This arrangement is also shown in the drawing in which the contact is made by pressing down the pin S until it contacts the armature V . A notch is provided in the pin S , adapted to be engaged by the pawl contact B , in such manner that the pin S can be moved back only after the pawl B is retracted through the intermediary of means such as an electromagnet N , the latter being adapted for actuation at will by the auction-master. Any source of current O, L may be provided by actuation of the electromagnet N .

Further the current circuit of the signalling lamp may be adapted to lock itself, which locking is only removed when the current circuit is interrupted by the auction master. As this may be effected with well known means a further description in detail of such arrangements will not be necessary.

I claim:

1. An electric signalling system having a current limiting means, comprising a main circuit including a source of current, and a plurality of branch circuits connected in parallel across said main circuit, each branch circuit including in series, a glow discharge tube with which the current limiting means is connected in series, and a switch, the glow discharge tube being activated by the switch first operated, producing, independently of any mechanically moving part, a potential drop in the main circuit across the current limiting means to a value insufficient to activate any other of the glow discharge tubes.

2. An electric signalling system comprising a main circuit including a source of current, a current limiting means, and a plurality of branch circuits connected in parallel across said main circuit, each branch circuit including in series, a glow discharge tube, with which the current limiting means is connected in series, and a switch, the glow discharge tube activated by the switch first operated producing, independently of any mechanically moving part, a potential drop in the main circuit, across said current limiting means, to a value insufficient to activate any of the other glow discharge tubes.

3. A device as claimed in claim 2, in combination with an automatic price indicator including means for stopping the indicator when a tube is energized.

4. An electric signalling system as claimed in claim 2, in which the current limiting means has such value that the lighting of one tube reduces the potential which thereafter may be impressed upon the other tubes to a point below the lighting potential of

each of the said other tubes, in combination with a bidding device with automatic price indicator, the potential difference between the terminals of said current limiting means being impressed upon the input circuit of a thermionic valve and a device in an output circuit of said valve adapted to stop the indicator.

5 5. An electric signalling system as claimed in claim 2, the said current limiting means having such value that the lighting of one tube reduces the potential which thereafter may be impressed upon the other tubes to a point below the lighting potential of each 10 of the said other tubes, means for locking the switches when depressed, and a control switch 15 separate from said contact devices for breaking the contact established by the switches in said parallel circuits.

20 6. An electric signalling system as claimed in claim 2, the current limiting means having such value that the lighting of one tube by the closing of its switch reduces the potential in said circuits which thereafter is available 25 to be impressed upon the other tubes, to a voltage below the lighting potential of said other tubes.

In testimony whereof I affix my signature.
MARTEN JOHANN HUIZINGA.
